CONVEYER SYSTEM CONTROL

Gerald Deakin, New York, N. Y., assignor to International Standard Electric Corporation, New York, N. Y., a corporation of Delaware

Application November 16, 1944, Serial No. 563,756

16 Claims. (Cl. 214—60)

1

The present invention relates to a control for a conveyer system and particularly to a control for a conveyer system in which individual units of the conveyer are arranged to automatically discharge their load at predetermined receiving stations.

More particularly still the invention relates to a control circuit so arranged that the major elements of the control are mounted in stationary positions at the various receiving stations and only a small portion of the control apparatus is carried by the individual moving units of the conveyer.

It is an object of the invention to provide a conveyer system of the automatic discharging type having a control, the major elements of which are located at the receiving stations.

It is another object of the invention to provide such a control system as that mentioned in which each unit of the conveyer carries settable devices and minor circuit elements whereby the unit may be conditioned for discharging its load at any one of a plurality of receiving stations.

Other objects and features of the invention will appear when the following description is considered in connection with the annexed drawings in which—

Figure 1 is an end elevation of a conveyer unit of a type to which my invention is applicable;

Figure 2 is a front elevation of the conveyer unit of Figure 1;

Figure 3 is a view similar to Figure 1 but showing the equipment in its discharging position after operation by the circuit of the present invention;

Figure 4 is a front elevation of the unit in the position illustrated in Figure 3;

Figure 5 is a schematic wiring diagram of the portion of the control circuit located on each conveyer unit; and

Figure 6 is a schematic wiring diagram of the portion of the control circuit located at each receiving station.

Referring now to Figures 1 through 4 which illustrate a preferred form of conveyer system to which my control may be applied, it will be seen that the conveyer comprises a pair of tracks 1 which are suspended adjacent each other by means of a bracket 2, or any other suitable support, which bracket is in turn affixed to an overhead surface as, for example, the ceiling 3 of the room. Obviously, the tracks may be supported in any other suitable manner and at any convenient height. Each conveyer unit comprises the hangers 4 which depend from the shafts 5 car-

2

rying rollers 6 which run on the tracks 1. The various units of the conveyer are attached to a cable 7 at spaced intervals therealong, the cable being driven in any well known and suitable manner.

The hangers 4 are formed at their lower ends to provide pivot points for pins 8 which pins are fixed to and extend from platform 9 on which the goods are placed, normally manually.

In accordance with my invention I provide on each conveyer unit a plurality of keys 10 (Figures 2, 4 and 5) together with a potentiometer 11 (Figure 5) and three contact brushes 12, 13 and 14 (Figures 1, 3 and 5).

At each receiving station I provide a contact unit comprising the three segmental contacts 15, 16 and 17 together with the circuit illustrated in Figure 6 and including the magnet or solenoid 18. The magnet 18 is provided with an armature 19 which is adapted to operate against the rod 20 and thereby oscillate the arms 21 of the unit counterclockwise about their pivot points 22 thereby causing the unit to discharge its load by virtue of the inclination of the platform 9, as illustrated particularly in Figures 3 and 4.

As has been indicated, the circuit elements provided on each conveyer unit comprise the potentiometer 11 which is tapped at various points and to which connection can be made by operation of the keys 10. Current is fed to the potentiometer through the brushes 12 and 14 and the potential existing at the brush 13 is determined in accordance with the operation of the keys 10. These keys 10 are preferably locking keys which will retain their closed position when set until released, either manually or automatically as the case may be. At each receiving station in addition to the contact segments 15, 16 and 17 there is provided a circuit including the rectifiers 23, 24 and 25, electron tube 26, potentiometer 27 and resistance 28. The rectifier units of the rectifiers 23, 24 and 25 are poled so that current will flow from positive to negative in the direction of the arrows. The filament 29 of tube 26 is heated by virtue of current supplied from a suitable source, shown in this instance as an A. C. source, through the transformer 30. A D. C. source could of course be used if desired.

The details of the circuit are best described by reference to the operation of the system. In setting up the system each receiving station is adjusted so that it will be rendered operative when a conveyer unit closes circuits through the contacts 15, 16 and 17 and brushes 12, 13 and 14 when a particular key 10 has been operated. This ad-

justment involves merely the setting of the variable contact 31 of potentiometer 27 to a position corresponding to the tap point which is connected by operation of the particular key 10 considered.

Let it be first assumed that the conveyer unit under consideration is travelling between receiving stations and that, therefore, no circuits are completed through the contacts 15, 16 and 17 and the brushes 12, 13 and 14, respectively. Under these conditions, current flows normally from the positive to negative terminal of rectifier unit 23 over one circuit including conductor 32 and potentiometer 27 and over another circuit including conductor 33, resistance 28, conductor 34, rectifier unit 25, conductor 35 to variable tap 31 and part of potentiometer 27 to the negative terminal of rectifier unit 23. The righthand side of rectifier unit 25 is thus made positive and the left side negative and current flows through two parallel paths, one including rectifiers 37 and 36 and the other rectifiers 39 and 38. Since rectifier 37 is positively polarized and rectifier 36 negatively polarized, the former has a low impedance and the latter a high impedance. Likewise, since rectifier 39 is negatively polarized and rectifier 38 positively polarized, the former has a high impedance and the latter a low impedance. Thus filament or cathode 29 of tube 26 is made positive with respect to grid 40 and no or a very small current flows from the cathode 29 to plate 47. It will be seen that the left side of rectifier 25 will be weakly or strongly negative according to the position of tap 31 on potentiometer 27.

Now if the unit arrives at a receiving station other than the one selected, a circuit will be completed which will apply positive potential over conductors 33 and 41 and through contact 15 and brush 12 to the upper terminal of potentiometer 11. Likewise, a circuit will be completed from the negative side of rectifier 23 over conductor 42 and contact 17 and brush 14 to the lower side of potentiometer 11. In addition, a circuit will be completed from the righthand end of the rectifier unit 25 over conductors 34 and 43, contact 16, brush 13 and conductors 44 and 45 to any operated key 10, and thence through that key to the corresponding tap point on potentiometer 11. Since the setting of the key does not correspond with the setting of variable contact 31 of potentiometer 27, there will be a difference of potential existing at the right and left ends of the rectifier unit 25. This difference in potential will operate in the manner described above in connection with the circuit through resistance 28 to provide a negative bias on tube 40 and this tube will continue to be non-conducting. If, for example, the potential existing on conductor 44, 45, brush 13, contact 16, conductor 43 and, therefore, at the righthand end of the rectifier unit 25 is more positive than that existing on contact 31 and at the lefthand end of rectifier 25, then due to the low impedance of rectifier 37 to current flow in that direction and the high impedance of rectifier 36 a relatively high positive potential will exist on the cathode 29 of tube 26. Likewise, because of the high impedance of rectifier 39 and the low impedance of rectifier 38 a relatively high negative potential will exist on grid 40 of the tube. It should be understood that in this event although the biasing resistance 28 is still in circuit, it is now substantially in parallel with the circuit through the potentiometer 11 and consequently the bias supplied by it is negligible.

When the conveyer unit under consideration

reaches the receiving station adjusted to correspond to the key operated upon the unit, the potential applied to the right and lefthand ends of rectifier unit 25 over the circuits previously described is substantially equal. Consequently the negative bias is removed from the grid 40 of tube 26 and current then flows through the circuit comprising rectifier 24, conductor 46, the two legs of filament 29 in parallel as a cathode, plate 47, conductor 48, magnet 18 and conductor 49. Operation of magnet 18, as has been described, causes operation of bar or roller 20 and elevation of the arms 21 so that these arms unlatch from the latching bars of the conveyer unit and permit the platform 9 to drop into the position shown in Figure 3 thereby discharging the load at the selected receiving station.

As has been stated hereinabove, platform 9 may be restored manually by the operator at the receiving station or may be automatically restored. Such automatic restoration can be effected by the use of a cam 50 (Figures 1 through 4) and a bracket such as 51 (Figure 1). It will be seen that when the carrier or conveyer unit in its traverse reaches a bracket such as 51, the camming surface 50 rides up on the bracket and restores the platform to its horizontal position causing the arms 21 to latch behind the latching bars.

The keys 10 may either be reset by the receiving station operator or may be automatically reset. Such automatic operation can be effected by utilizing keys of the latching type having slides which may be operated by cam surfaces connected to the platform 9 either upon the restoration or operation thereof.

While I have described a preferred embodiment of my invention, many different forms thereof may be utilized and, therefore, I wish to be limited not by the foregoing description but solely by the appended claims.

What is claimed is:

1. In a control circuit for causing the unloading of a conveyer at any one of a plurality of points on its traverse, in combination a tapped potentiometer on the conveyer, settable means for selecting one of said taps, a variable potentiometer at each unloading point, means for adjusting said last mentioned potentiometer to correspond with the setting of any one of said settable means, means at each unloading point to supply an operating voltage to said potentiometers in parallel, an impedance unit comprising two parallel branch circuits each including two oppositely poled uni-directional impedances in series, the impedances of one branch being reversely poled with respect to corresponding impedances in the other branch, whereby current flow in either direction through said unit causes the common terminal of the two impedances in one branch to have a relatively higher positive potential than the corresponding point in the other branch, means connecting one terminal of said impedance unit to the tap point on said conveyer potentiometer, and means connecting the other terminal of said impedance unit to the unloading point potentiometer whereby when the potentiometers are similarly adjusted no current flows and the two common connections between impedances in the branches of the impedance unit are at the same potential.

2. In a control circuit for causing the unloading of a conveyer at any one of a plurality of points on its traverse, in combination a potentiometer on the conveyer, a plurality of taps on

said potentiometer, settable means for selecting one of said taps, a potentiometer at each unloading point, a variable contact on each said potentiometer, an impedance unit comprising two parallel branch circuits each including two oppositely poled unidirectional impedances, the impedances of one branch being reversely poled with respect to those in the other branch, whereby current flow in either direction through said unit causes the common terminal of the two impedances in one branch to have a relatively positive potential with respect to the corresponding point in the other branch, means to supply an operating voltage to said unloading point potentiometers, commutator means for supplying the same operating voltage to said conveyor potentiometers when the conveyer is at an unloading point, commutator means for supplying the potential from a selected tap point on said conveyer potentiometer to one terminal of said impedance unit, and means for supplying the potential from the variable contact of said unloading point potentiometer to the other terminal of said impedance unit.

3. In a control circuit for causing the unloading of a conveyer at any one of a plurality of points on its traverse, in combination, a potentiometer on the conveyer, a plurality of taps on said potentiometer, settable means for selecting one of said taps, a potentiometer at each unloading point, a variable contact on each said potentiometer, an impedance unit comprising two parallel branch circuits each including two oppositely poled unidirectional impedances, the impedances of one branch being reversely poled with respect to those in the other branch, whereby current flow in either direction through said unit causes the common terminal of the two impedances in one branch to have a relatively positive potential with respect to the corresponding point in the other branch, means to supply an operating voltage to said unloading point potentiometers, commutator means for supplying the same operating voltage to said conveyor potentiometer when the conveyer is at an unloading point, commutator means for supplying the potential from a selected tap point on said conveyor potentiometer to one terminal of said impedance unit, means for supplying the potential from the variable contact of said unloading point potentiometer to the other terminal of said impedance unit, and potential responsive means connected across the common terminals of the two impedances of one branch circuit of said impedance unit and the common terminal of the two impedances in the other branch of said impedance unit, whereby when the unloading point potentiometer and the conveyer potentiometer are similarly set no current flows through the impedance unit and the potential responsive device is operated.

4. In a control circuit for causing the unloading of a conveyer at any one of a plurality of points on its traverse, in combination, an impedance unit at each unloading point, each unit comprising two parallel branch circuits, each including two oppositely poled unidirectional impedances, the impedances of one branch being reversely poled with respect to those in the other branch, whereby current flow in either direction through said unit causes the common terminal of two impedances in one branch to be at a relatively higher positive potential than the corresponding point in the other branch, means for normally causing current flow through said impedance unit, and a potential responsive device connected across the

common impedance terminals of the two branches, said device being normally biased to inoperative condition, and means operable upon the conveyer reaching a selected unloading point to cause cessation of current flow through said impedance unit and operation of said potential responsive device.

5. In a control circuit for causing the unloading of a conveyer at any one of a plurality of points on its traverse, in combination, an impedance unit at each unloading point, each unit comprising two parallel branch circuits, each including two oppositely poled unidirectional impedances, the impedances of one branch being reversely poled with respect to those in the other branch, whereby current flow in either direction through said unit causes the common terminal of two impedances in one branch to be at a relatively higher positive potential than the corresponding point in the other branch, means for normally causing current flow through said impedance unit, a triode having its grid-filament circuit connected across the common impedance terminals of the two branches, said triode being normally biased to inoperative condition, means operable upon the conveyer reaching a selected unloading point to cause cessation of current flow through said impedance unit and operation of said triode, and magnetic means in the plate circuit of said triode for operating said conveyer to unloading position.

6. In a control circuit for causing the unloading of a conveyer at any one of a plurality of points on its traverse, in combination, an impedance unit at each unloading point, each unit comprising two parallel branch circuits, each including two oppositely poled unidirectional impedances, the impedances of one branch being reversely poled with respect to those in the other branch, whereby current flow in either direction through said unit causes the common terminal of the two impedances in one branch to be at a relatively higher positive potential than the corresponding point in the other branch, means for normally causing current flow through said impedance unit, a potentiometer on said conveyer, taps on said potentiometer, settable means for selecting one of said taps, a potentiometer at each unloading station, a variable contact on each unloading station potentiometer, means for applying an operating potential to said unloading station potentiometers, commutator means for applying said operating potential to the conveyer potentiometers, means connecting the variable contact of each unloading station potentiometer to one terminal of said impedance unit, commutator means for connecting the selected tap of the conveyer potentiometer to the other terminal of said impedance unit when said conveyer reaches any unloading station, and a triode having its grid filament circuit connected across the common impedance terminals of the two branches, said triode being normally biased to inoperative condition, means operable upon the conveyer reaching a non-selected unloading point to apply a higher potential to one terminal of said impedance unit than to the other and continue the bias upon the triode, and means operable upon the conveyer reaching a selected unloading station to apply equal potentials to the terminals of the impedance unit to remove the bias from said triode.

7. In a control circuit for causing the unloading of a conveyer at any one of a plurality of points on its traverse, in combination, an impedance unit at each unloading point, each unit comprising two parallel branch circuits, each includ-

ing two oppositely poled unidirectional impedances, the impedances of one branch being reversely poled with respect to those in the other branch, whereby current flow in either direction through said unit causes the common terminal of the two impedances in one branch to be at a relatively higher positive potential than the corresponding point in the other branch, means for normally causing current flow through said impedance unit, a potentiometer on said conveyer, taps on said potentiometer, settable means for selecting one of said taps, a potentiometer at each receiving station, a variable contact on each unloading station potentiometer, means for applying an operating potential to said unloading station potentiometers, commutator means for applying said operating potential to the conveyer potentiometers, means connecting the variable contact of each unloading station potentiometer to one terminal of said impedance unit, commutator means for connecting the selected tap of the conveyer potentiometer to the other terminal of said impedance unit when said conveyer reaches any unloading station, and a triode having its grid-filament circuit connected across the common impedance terminals of the two branches, said triode being normally biased to inoperative condition, means operable upon the conveyer reaching a non-selected unloading station to apply a higher potential to one terminal of said impedance unit than to the other and continue the bias upon the triode, means operable upon the conveyer reaching a selected unloading station to apply equal potentials to the terminals of the impedance unit to remove the bias from said triode, and magnetic means in the plate circuit of said triode operable to release the conveyer to discharging position.

8. In a control system for a conveyer of the type wherein it is desirable to unload the conveyer at a selected one of a number of unloading stations, a control circuit assembly including, two separate voltage dividers adapted to be connected in parallel and each being adapted to provide voltages corresponding to one of the unloading stations, circuit means to connect together the voltages of the two voltage dividers, said circuit means including a rectifier unit formed by two branch circuits connected in parallel with each branch including two oppositely poled rectifier elements connected together at a common terminal and with one branch circuit being connected reversely with respect to the other branch circuit, whereby current flowing through said rectifier unit in either direction causes a difference in potential between the common terminals in the two branch circuits, and means responsive to the absence of a potential difference between said common points resulting from the cessation of current flow through said rectifier unit.

9. Apparatus as described in claim 8 wherein the last-named means comprises, an electronic device having a controlled circuit and a control grid which grid is biased to prevent the flow of current through the controlled circuit when there is current flow through the rectifier unit, and an electromagnet connected in said controlled circuit to be energized and perform the unloading operation upon the flow of current through the controlled circuit.

10. In control mechanism for a conveyer system where it is desirable to provide for the delivery of various units of material at different stations, the combination of: a plurality of mov-

able elements adapted to move individually with the various units of material and to be energized to produce various output potentials identified respectively with the various stations; a plurality of station assemblies identified respectively with the various stations and each including, a potential-source unit which is adapted to produce an output potential identifying its particular station, an impedance assembly comprising two parallel circuits each of which is formed by two impedance units each having the characteristic that the impedance is different when the current flows in one direction than when the current flows in the other direction with the two units of each parallel circuit being connected reversely and connected together at a common terminal and with the two parallel circuits connected reversely whereby the flow of current through said impedance assembly in either direction causes a potential difference to exist between said common terminals, and relay means responsive to a predetermined potential difference between said common terminals to effect delivery of selected units of material to the station; and circuit means which is effective when each movable element approaches a station to connect the output potential of that movable element to the output potential of the potential-source unit of that station with the connection being through the impedance assembly of that station.

11. Apparatus as described in claim 10 wherein the relay means at each station assembly comprises an electronic amplifying means with an input circuit connected to said common terminals and an output circuit, and delivery means connected to said output circuit.

12. In apparatus of the character described wherein it is desirable to unload a conveyer at a selected unloading station, a control circuit comprising, a movable voltage divider carried by the conveyer and adapted to produce an output potential identified with a particular unloading station, a stationary voltage divider positioned at said unloading station and adapted to provide an output potential which identifies the unloading station, a potential-responsive circuit including a contact assembly which is closed when the conveyer is positioned to be unloaded at said unloading station thereby connecting the output potential of said movable voltage divider to the output potential of said stationary voltage divider, whereby there is a flow of current through said circuit when the two output potentials are not the same, and means responsive to a predetermined current flow through said circuit to initiate the unloading operation.

13. In apparatus of the character described wherein it is desirable to unload a conveyer at a selected unloading station, a control circuit comprising a pair of voltage dividers adapted to be connected in parallel and upon energization from a single voltage source to provide in an output circuit from each voltage divider a predetermined potential identified with a particular unloading station, means to supply said voltage dividers with a predetermined voltage, and an impedance means connecting said output circuits together, whereby a current flows through said impedance means when there is a difference in the output potentials of the two voltage dividers, said impedance means comprising two parallel branch circuits each having a central terminal the potential of which is changed by a change in the flow of current therethrough with the change being greater for any given change in current value

when the current flows in one direction than when the current flows in the other direction, said parallel branch circuits being reversely connected whereby the two central points have their voltages changed by different amounts when there is a change in the rate of current flow.

14. In a control system for a conveyer of the type wherein there are a number of stations at which materials from the conveyer may be unloaded and it is desirable to select the station for the unloading of each unit of material prior to the arrival of the unit of material to the station, the combination of, a plurality of stationary circuit assemblies corresponding in number to the unloading stations and each having contactor means positioned at its respective station, and a plurality of movable units each adapted upon energization to produce a distinctive output potential said movable units being mounted respectively to move with the various units of material and having movable contactor means positioned respectively to engage the various contactor means at the respective unloading stations, each of said stationary circuit assemblies including means constituting a source of potential which is supplied to the various movable units through said contactor means as the various movable units are positioned at the respective unloading stations, each of said stationary circuit assemblies also including an impedance assembly and a stationary unit connected to the source of potential and having an output potential circuit connectable through said impedance assembly and said contactor means to the output potential of each of the movable units, said impedance assembly comprising two parallel circuits each formed by a pair of impedance units the impedance of each of which is greater when the current flows in one direction than when flowing in the other direction with the impedance units of each parallel circuit being reversely coupled at a common terminal whereby for any given value of current flow the potential of the common terminal is different when the current is flowing in one direction from what it would be if the current were flowing in the opposite direction, said

parallel circuits being reversely connected whereby the two common terminals have opposite potential variations with any given change in current flow, whereby current flow through said impedance assembly produces a potential bias between said common terminals which potential bias is in the same direction regardless of the direction of flow of current through said parallel circuits, and each of said stationary assemblies 5 also including means responsive to the existence of a zero potential bias between said common terminals to identify the arrival of the units of material to be unloaded at that particular station.

15. 15. In a conveyer system of the type wherein there are a number of stations at which materials may be unloaded and signal means is provided on the conveyer to move with each unit of material to produce a distinctive voltage indicating that that particular unit of material is to be unloaded at a particular station and wherein each station is provided with means to produce a distinctive potential, an impedance means positioned at a station and adapted to be connected between the potential produced by the signal means on the conveyer and the potential produced at the station, said impedance means comprising two parallel branch circuits each formed by two oppositely poled unidirectional impedances with one branch circuit being reversely poled with respect to the other branch circuit, whereby a current flow through the circuits in either direction causes the common terminal of the two impedances in one branch circuit to be at a relatively higher positive potential than the corresponding point in the other branch circuit.

20 16. Apparatus as described in claim 15 which includes, an electronic device having a controlled circuit and a control grid which control grid is 25 connected to be biased by the potential difference existing between said common terminals thereby to prevent the flow of current through the controlled circuit, and means responsive to the flow of current through said controlled circuit to unload the conveyer.

GERALD DEAKIN.
